MUNTING AND CROSS JOINT ANCHORAGE

Ward P. Kessler, Bristol, Ind., assignor to Victor
M. Langsett, Chicago, Ill., as trustee

Application November 7, 1946, Serial No. 708,286

3 Claims. (Cl. 189—36)

1

This invention relates to improvements in means and methods of attaching and anchoring the muntins in a window sash to the cross and side rails of the sash, as well as the muntins themselves where they cross one another.

The particular form and joinery of the cross and side rails of the sash are set forth in my co-pending application Serial No. 700,693 filed October 2, 1946.

The muntins are preferably made of formed metal or metal alloy sections by extrusion but it is readily apparent that any formed material, plastics for example, may be used.

An object of my invention is to provide means for joining the muntins in a window sash to the rails, and to themselves, where they cross, by adapting the contacting ends of the muntins to the adjacent contours of the rails and cross muntin, thereby interlocking the members, and imparting further rigidity to the structure, by mutilating or embossing an obtrusion on the rail or cross muntin adjacent to the muntin end.

Another object is to provide a mechanical assembly thereby avoiding welding or brazing the members.

Another object is to permit the surface finishing of the muntins before assembly.

Another object is to provide an efficient and cost reducing method of installing the muntins in the sash after the rails have been assembled.

A further object is to provide means for fastening the muntin ends without affecting the structural strength of the sash rails and cross muntins.

Further objects and advantages of the invention will be apparent from the following specification and the accompanying drawings, wherein a preferred embodiment of the invention has been shown and described.

In the drawings:

Figure 1 is a perspective view of a cross sash rail and vertical muntin joined.

Figure 2 is a perspective view of the form and end treatment of the muntin.

Figure 3 is a side view of the muntin end shown in Figure 1.

Figure 4 is a side view of the cross sash rail and muntin in position, showing the method of mutilating and distorting an obtrusion on the cross rail, thereby holding the muntin in place.

Figure 5 is a side view of the muntin end joinery taken at right angles to the axis of the cross rail, which is shown in cross-section.

Figure 6 is similar to Figure 5, showing the mutilating and distorting of the obtrusion on the cross rail.

2

Figure 7 is a perspective view of a cross muntin and the upper vertical muntin joined.

Figure 8 is a perspective view of a side sash rail and muntin end joined, the muntin form varying from that shown in Figure 1.

Figure 9 is a side view of the structure shown in Figure 8, more clearly showing the mutilation and distortion of the obtrusion on the side rail.

Figure 10 is a top view of the muntin showing the end treatment.

Figure 11 is a top view taken at right angles to the axis of the side rail, which is shown in cross-section, showing the mechanical joinery.

Figure 12 is similar to Figure 11, more clearly showing the distortion of the obtrusion on the side rail adjacent to the muntin end.

The complete window sash has not been shown in the drawings, but it should be obvious that any sash has a plurality of side rails and cross rails, usually two side rails and an upper and lower cross rail, the muntins which may be vertical or horizontal, or both, or, in some instances, on the diagonal.

Similar numerals refer to similar parts throughout the several views.

Referring to Figures 1 to 6 inclusive, of the drawings, the sash cross rail 1, substantially rectangular in cross-section, preferably with a hollow center, has one side wall with an inturned L-shaped elongation 2 and the obtrusion 3 on the adjoining side wall nearest said elongation, the outside surfaces of said obtrusion 3 and the in-turned lip of the elongation 2 being substantially on the same plane, forming the recess 4.

The vertical muntin to be attached to said rail 1, an end portion of which is shown at 5, has a base 6, the stem 7 and the head 8 with both ends inturned, forming a block letter T in cross-section.

The end surface of said muntin is formed at right angles to the axis of the muntin, so as to rest firmly upon the exterior face of the cross rail 1, to which it is locked. To form the jointure means, a channel 9 is formed in the head and in-turned legs of 8 and the stem 7, at right angles to the axis of said muntin, at a height, and to a depth and width to accommodate and intimately embrace the in-turned lip of the elongated leg 2 of the rail 1 and another channel 10 is formed in the in-turned legs of the head 8 and the stem 7, to a width and depth to accommodate and intimately embrace the obtrusion 3 on the rail 1. To assemble the muntin and rail, a portion of the obtrusion 3 of the rail 1 is removed a short distance from the final position of the muntin, as at

11, permitting the formed end of the muntin to be placed into position for telescoping upon the inturned leg 2 and obtusion 3 of the rail 1. The muntin is then moved along the axis of the rail to the desired position, the channels 9 and 10 conforming to and intimately embracing the in-turned lip of the leg 2 and obtusion 3, respectively, of the rail 1, thereby interlocking the muntin in place. Further lateral movement of the muntin is prevented by mutilating and distorting 10 the obtusion 3 on both sides of its point of contact with the stem 7 of the muntin 5, as at 12, 12, thereby firmly fixing it in position and adding rigidity to the structure.

Referring now to Fig. 1 for example, it should be noted that the terminal edges of the legs or flanges on the sash rail and also on the muntin terminate in a common plane when assembled as shown in Fig. 1. Thus these edges provide co-planar surfaces against which the inner surfaces of flat planes of glass may be abutted, after which putty or other glazing compositions may then be applied to the juncture of the opposite surfaces of the glass and the adjoining surfaces of the muntin and sash rail, as is customary. The sheared notch 11 and the swaged or upset portion 12 of the ridge 3 will of course be concealed by the glazing composition.

It is obvious that similar joinery may be used in attaching the muntins to other rails in the sash.

Where both horizontal and vertical muntins are used in the sash, provision must be made for the cross joints. This form of joinery is shown in Figure 7. In the interest of structural strength, the horizontal muntin 13 is one continuous length. This muntin 13 is of similar form to the vertical muntin 5, with the addition of the obtusions 14, 14, on both sides of the stem 7, thereby forming a recess and arrangement similar to that of the in-turned leg 2 and obtusion 3 of the rail 1. The end of the vertical muntin section is formed and the assembly of the cross joint is completed as described above, further movement of the vertical muntin section being prevented by the mutilation of the obtusion 14 on both sides of the stem 7, as shown at 15, 15.

It is apparent from the foregoing description, that the muntins may be surface finished and installed in the sash frame after the rails have been assembled, thereby facilitating the manufacturing process. Furthermore, the interlocking of the prepared muntin ends with the contours of the rails and cross-muntins, and mechanical immobilization, makes welding or brazing unnecessary, thereby substantially reducing the cost of the assembly.

Where diagonal muntins are used in a sash, it is obvious that similar means and methods described above may be used, the muntin ends, channels 9 and 10 being formed on a bias to conform to the angles desired and the particular sash design.

In Figures 8 to 12, inclusive, a form of muntin is shown varying from that disclosed in previous figures. This form is adaptable where no cross muntin is used. One side of the side rail 16 has an elongated inturned leg 17, and the side adjacent thereto, an obtusion 18, forming the recess 19, the exterior surfaces of the inturned lip of the leg 17 and the obtusion 18 being substantially in the same plane. The muntin 20 has a stem 21 with the heads 22 and 22' at each end thereof and at substantially right angles thereto. The ends of these heads 22, 22' are inturned, forming a

glazing support and recess for putty retention. The end surface of said muntin is formed at right angles to the axis of the muntin, so as to rest firmly upon the exterior face of the side rail 16, to which it is locked. To form the jointure means, a channel 23 is formed in the head and inturned legs, 22, and the stem 21, transverse to the axis of said muntin, at a height and to a depth and width to accommodate and intimately embrace the inturned lip of the leg 17 of the rail 16 and another channel 24 is formed in the in-turned legs of the head 22 and the stem 21, to a depth and width to accommodate and intimately embrace the obtusion 18 of the rail 16. The muntin and rail are then interlocked as herein-before described, the channels 23 and 24 conforming to and intimately embracing the in-turned leg 17 and obtusion 18 respectively, and mechanically held in position by the mutilation or distortion of the obtusion 18 on both sides of the muntin as indicated at 25, 25.

While I have shown and described herein, for illustrative purposes, a preferred and alternative embodiment of the invention and methods of practicing it, it should be understood that considerable variation in the details of construction may be employed and the method varied, without departing from the spirit and scope of the invention, as set forth in the following claims.

I claim as my invention:

1. In combination, an extruded rigid sash rail having a vertical wall and integral therewith a longitudinally extending inturned flange perpendicular to said wall, said rail having a second wall perpendicular to the first wall spaced from and parallel to said flange, an obtusion on said second wall in the form of a longitudinally extending shearable ridge projecting therefrom toward said flange but terminating short thereof by a distance at least equal to the height of said ridge, the ridge being spaced from said first wall a distance equal to the thickness of the head wall of a muntin now to be mentioned, and an extruded muntin of T form in cross section having a head wall and a web wall perpendicular thereto, said head wall having inturned marginal flanges, one end of said muntin being seated on said rail second wall, the muntin near said end having a transverse slot through its head wall portion proportioned to snugly yet slidably embrace the flange of said first rail wall and being notched at said end to slidably embrace said ridge while the end of the head wall of the muntin extends into the recess between the ridge and said first rail wall, a portion of the ridge located laterally of the final desired location of the muntin end being cut away flush with the second rail wall to facilitate insertion of the notched end of the muntin between the ridge and first wall by lateral sliding movement of the muntin with said slot slidably engaging said rail flange, the rail ridge being swaged against the muntin to lock the latter in fixed final position.

2. In combination, an extruded rigid sash rail having a vertical wall and integral therewith a longitudinally extending inturned flange perpendicular to said wall, said rail having a second wall perpendicular to the first wall spaced from and parallel to said flange, an obtusion on said second wall in the form of a longitudinally extending shearable ridge projecting therefrom toward said flange and underlying said flange and spaced apart from said first wall, and an extruded muntin of substantially block letter T form in transverse cross section, the T head portion of

the muntin having inturned marginal flanges, one end of said muntin being seated on the second wall, the muntin near said end having a transverse slot through its T head portion proportioned to snugly yet slidably embrace the flange of said rail vertical wall and being vertically notched at said end to slidably embrace said ridge while the end of the T head extends into the space between the ridge and said first wall, a portion of said ridge in an area located laterally of the final desired location of the muntin end being cut away flush with the second wall to facilitate insertion of the notched end of the muntin between the ridge and first wall by lateral sliding movement of the muntin with said slot slidably engaging said rail flange, and means operative to restrain movement of the muntin laterally relative to the sash rail.

3. In combination, an extruded rigid sash rail having a vertical wall and integral therewith a longitudinally extending inturned flange perpendicular to said wall, said rail having a second wall perpendicular to the first wall spaced from and parallel to said flange, an obstruction on said second wall in the form of a longitudinally extending shearable ridge projecting therefrom toward said flange and wholly underlying said flange but terminating short thereof by a distance at least equal to the height of said ridge, the ridge being spaced from said first wall a distance equal to the thickness of the head wall of a muntin now to be mentioned, and an extruded muntin of T form in cross section having a head wall and a

25

30

web wall perpendicular thereto, said head wall having inturned marginal flanges, one end of said muntin being seated on said rail second wall, the muntin near said end having a transverse slot through its head wall portion proportioned to snugly yet slidably embrace the flange of said first rail wall and being notched at said end to slidably embrace said ridge while the end of the head wall of the muntin extends into the recess between the ridge and said first rail wall, a portion of the ridge located laterally of the final desired location of the muntin end being cut away flush with the second rail wall to facilitate insertion of the notched end of the muntin between the ridge and first wall by lateral sliding movement of the muntin with said slot slidably engaging said rail flange, the rail ridge being swaged against the muntin to lock the latter in fixed final position, the terminal edges of said inturned flanges of the rail and muntin lying in a common plane to constitute abutment surfaces against which glass panes may be abutted.
